UNITED STATES PATENT OFFICE.

GEORGE M. ARRAGG, OF LAWRENCE, MASSACHUSETTS.

STOP-MOTION.

1,168,457.

Specification of Letters Patent.

Patented Jan. 18, 1916.

Application filed January 28, 1915. Serial No. 4,877.

To all whom it may concern:

Be it known that I, GEORGE M. ARRAGG, a subject of the Empire of Turkey, residing at Lawrence, in the county of Essex and State of Massachusetts, have invented certain new and useful Improvements in Stop-Motions, of which the following is a specification.

This invention relates to stop motions for 10 textile machines which operate on roving or yarn.

It is particularly applicable to spinning frames of various kinds especially to such machines wherein there are front and back 15 drawing rolls through which the roving passes and from which it is delivered to twisting or spinning mechanism and wound upon a bobbin. Its purposes are to disengage the roving from the first or back drawing rolls which act as feed rolls and to break 20 it at that point of delivery, so that if a break occurs between the back and front rolls or between the front rolls and bobbin, the roving will cease to be delivered. Thereby, 25 when a break occurs there will be very little waste and the roving will not be delivered in such a manner as to become entangled with the machinery or soiled by contact with the machine frame or floor.

With my device an operator can tend 30 more machines. He is also in less danger from accidents which frequently occur in clearing the roving from the roll in case of a broken end which winds up thereon. In 35 clearing such roving there is great danger that the operator's fingers will be pulled in. There is less likelihood of injury to the machinery also, as the operator frequently pounds the rolls in the effort to clear the 40 roving. There is a great saving in waste which means also a saving in the cost of picking up the waste, cleaning and picking it over.

My device also prevents laps and what is 45 known as double spinning, where an end breaks and in some way gets mixed up with an adjoining end, thereby spoiling both or, if not discovered in time, spoiling cloth by making defective work.

My device is particularly applicable to 50 cap spinning machines and in the drawings herewith I show it attached to such a cap spinning machine for worsted yarn.

In the drawings, Figure 1 is a diagrammatic side elevation of a cap spinning machine with my device attached. Fig. 2 is a

plan view of part thereof showing two rocking members on the left in running position and one on the right after an end has broken and it has been pushed over to stop the machine. Fig. 3 is a rear elevation of part of the vibrator. Fig. 4 is a detail side elevation enlarged of the back rolls and connections. Fig. 5 is a rear elevation of the back drawing rolls. Fig. 6 is a detail elevation 60 and Fig. 7 a detail plan view of the stretcher plate. Fig. 8 is a detail of the top carrier rolls. Fig. 9 is a modification of the setting mechanism.

A represents the frame of a spinning machine.

B represents the cap, C the bobbin, E the roving spool, F and G the back drawing rolls, H the top carrier rolls and M the bottom carrier rolls, K and L the front drawing 70 rolls all substantially of usual construction, and N represents the roving.

The bottom back drawing roll G is positively driven by any usual means as is also the bottom front drawing roll L. The top 80 front drawing roll K may be of any usual construction. For each strand or plurality of strands of roving which are to be twisted into a single end, I use a separate top back drawing roll F. Each is carried by a hanger 85 20 slidable through a hanger frame 21. Through each hanger 20 passes a hanger pin 22 into frame 21, the hanger being slidable thereon. Around pin 22 between hanger 20 and an adjusting nut 23 is a back roll spring 90 24 which tends to keep the top back drawing roll F in engagement with the bottom back drawing roll G, whereby the yarn or roving N will be drawn in and delivered in the usual manner.

Fixed to any suitable rail or bar 30 fixed to the frame of the machine are one or more L shaped plates 31 with a horizontal shelf 32. For each back top roll F, I provide a lifting plate 33 pivoted to 31 with its free 100 end at a point between rolls F and G not touching either. The roving N passes between the end 34 of this lifting plate and top roll F.

A compression spring 35 between lifting 105 plate 33 and shelf 32 would force plate 33 upward into engagement with roll F as shown by the dotted lines in Fig. 4 were it not for restraining means which I will now describe. On the frame of the machine 110 substantially below each lifting plate 33 is fixed a stretcher plate 40 with a forward

and back slot 41 and a shoulder 42 which projects thereinto. A flexible member 44 which may be a chain or wire rope is fastened at one end to the bottom of lifting plate 33 and extends downward therefrom, preferably through lifting plate spring 35, and through shelf 32 downward through slot 41 thence at a substantially sharp angle backward to some part of the frame where 5 the other end is fastened. This end is preferably fastened to spool 36 on shaft 9 which extends across the machine and forms part of the adjusting mechanism operated by a hand wheel 37. The spools and wheel are 10 revoluble whereby the flexible member may be wound up or unwound by revolving hand wheel 37 on which are suitable graduations. Locking means 38 as a pawl and ratchet are 15 preferably used to retain the parts in position. Transversely of the machine approximate to and preferably under the stretcher plates 40, I place a vibrator rod 50 which carries fingers 51 which extend upward and 20 preferably partly over each stretcher plate 25 40 in proximity to the member 44 and under the end of a rocking member. This vibrator 30 moves back and forth continually through the medium of a strap 52 and eccentric 53 carried by shaft 54 driven by pulley 55 and belt 56 from a main driving shaft 57.

Pivoted medially of its length to the frame at 61 is a rocking member 60 the back end of which is movable up and down into 35 the path of the vibrator fingers 51 in close proximity to the upwardly extending part of flexible member 44. The front end 62 of rocking member 60 is preferably T shaped as shown in Fig. 2 and preferably has a hole 40 63 through which the roving passes. This 45 rocking member is so placed and balanced that the action of the roving passing down from the front rolls to the bobbin will depress the front end and raise the back end 50 above the path of fingers 51 as shown clearly in Fig. 1 and Fig. 3.

If the roving breaks between the back rolls and bobbin, the tension on the front 55 of the rocking member ceases and as its back end is longer and heavier, that end drops into the dotted position shown in Fig. 3. In this position, it will be struck at the next movement of the adjoining finger 51 and will be pushed over against the flexible member 44 pushing it sidewise off from the shoulder 42 if it is caught thereover. The pivot at 61 is preferably loose so as to allow the rocking member 60 not only to move vertically but to some extent horizontally. 60 The shoulder 42 is at the front of the slot 41 and on the side adjoining the vibrator finger. As the back end of flexible member 44 is fixed, it is manifest that if it is pulled forward and caught over shoulder 42, it will 65 pull downward lifting plate 33 against

spring 35 and will hold it in that position until member 44 is pushed off from the shoulder 42 into the main slot 41.

As the lifting plate spring 35 is much stronger than the top roll spring 24, if not held down, the lifting plate will lift the top roll to the position shown in the dotted lines wherein it is separated from the bottom roll and moreover the roving end will be pinched between the end 34 of the lifting 75 plate and the surface of the top roll F and so held that the pull of the front rolls K and L will break it between the front and back rolls.

Starting with the flexible member caught 80 over the stretcher plate, it will be seen that if an end breaks allowing rocking member 60 to drop into the path of the vibrator, the action of the vibrator will push the end of the rocking member sidewise pushing off 85 the flexible member from the shoulder thus releasing lifting plate 33 whereby the top roll will be lifted and the roving stopped. No more roving can be delivered until the lifting plate is reset and the top back roll 90 drops back into place.

I prefer to use in slot 41 a spool 46 which has top and bottom flanges projecting over the sides of the slot as shown in Figs. 6 and 7 and a double trumpet shaped central passage through which passes the flexible member 44. This spool reduces the wear on the flexible member and makes it easier to operate.

I might reset the lifting plate by reaching 100 in with the fingers or hand and pulling the flexible member forward and to the side until it caught over shoulder 42 but I prefer to use a setting member. One form of setting member is shown at 70 in Figs. 1 and 105 2. It comprises a rod 70, for each end, which runs forward and back adjoining the stretcher plate and carries at its back a carriage 71 which has an oblique forward edge 72 which crosses slot 41. When this setting member is pulled forward by its rod 70, the front end of which may be curved at 73 to form a handle at the front of the machine, if the flexible member is in the slot 41, it will be pulled forward and slid over onto shoulder 42 where it will remain after the setting member has been pushed back. To facilitate the piecing of the ends after a break, I prefer to attach a slanting plate of metal 74 to the back of carriage 71 in such position that as the carriage is pulled forward, this piece of metal will act as a raising plate and lift the back end of rocking member 60. It keeps it raised until the carriage 71 is pushed back.

I might use a returning spring in connection with my setting means but prefer not to do so as in using the raising plate for the back end of the rocking member in connection therewith, it is better to leave the

setting means in the forward position until the ends are pieced.

The bottom carrier rolls are of the usual type, but, as shown in Fig. 8, instead of the usual form of top carrier rolls H, I prefer to have independent rolls 80 mounted loosely on a rod or shaft 81 so that when one end breaks, there will be no interference with the other ends. As instead of mounting my front and back rolls in pairs, I mount each one singly, it is desirable that the carrier rolls should also be singly mounted.

In Fig. 9, I show another form of setting mechanism which comprises a bell crank having a horizontal member 90 and vertical member 91 pivoted at their junction to the frame of the machine the front end of 90 projecting at the front of the machine where it can be easily reached by the operator. The vertical member is pivoted to a connecting rod 92 which is pivoted at its other end to carriage 71.

My vibrator as shown includes the rod 50, fingers 51, strap 52, eccentric 53, shaft 54 and the driving means but it is clear that any other of the well known forms of vibrator mechanism may be used in place thereof.

The mechanism for adjusting the length of the flexible member is particularly useful when as shown in Fig. 1 a longer ratch is desired and the back rolls are moved backward and upward to the dotted position shown. In such case, it is necessary to increase the length of the flexible member. This is done by unlocking the adjusting handwheel 37 and turning it with its spools 36 unwinding the flexible member to the extent desired.

To facilitate replacing the flexible member over the shoulder 42, its spool 36 is not directly behind it but somewhat more toward the shoulder side as shown in Fig. 3.

To keep member 44 from slipping off, the spools preferably have flanges or heads as shown.

My device is especially adapted for use on cap, ring and flier spinning machines.

The usual driving mechanism is used but is omitted for the sake of clearness.

I claim:

1. In a worsted spinning machine having a frame and a bobbin, a positively driven bottom back drawing roll, a spring-pressed frictionally driven top back drawing roll movable thereto and therefrom, a pivoted lifting plate adapted to lift the spring-pressed top back drawing roll, a spring which so engages said plate as to cause it to lift the spring-pressed drawing roll, a vibrator, a stretcher plate having a slot with a shoulder, a flexible member which passes through the stretcher plate slot and is fastened at one end to the frame of the ma-

chine and at the other end to the lifting plate, a medially pivoted rocking member of which one end is between the flexible member and the vibrator and the other end of which engages the roving between the bobbin and the drawing rolls, and setting means operative from the front of the machine to engage the flexible member with the shoulder of the stretcher plate.

2. In a worsted spinning machine having a frame and a bobbin, a positively driven bottom back drawing roll, a spring-pressed frictionally driven top back drawing roll movable thereto and therefrom, a pivoted lifting plate adapted to lift the spring-pressed top back drawing roll, a spring which so engages said plate as to cause it to lift the spring-pressed drawing roll, a vibrator, a stretcher plate having a slot with a shoulder, a flexible member which passes through the stretcher plate slot and is fastened at one end to the frame of the machine and at the other end to the lifting plate, a medially pivoted rocking member of which engages the roving between the bobbin and the drawing rolls, and setting means which comprise a handle operative from the front of the machine, a slideable carriage operative thereby having an oblique forward edge in operative relation with the flexible member, and a slanting raising plate attached to the carriage as described.

3. In a spinning machine, the combination of a bottom back drawing roll, a frictionally driven top back drawing roll spring-pressed thereon, a lifting plate, and a lifting plate spring, with a vibrator, a stretcher plate having a slot and a shoulder, a flexible member which passes through the slot in the stretcher plate and is fixed at one end and is attached at the other end to the lifting plate, and a medially pivoted rocking member having one end in engagement with the roving and the other end between the vibrator and the flexible member.

4. In a spinning machine, the combination of a bottom back drawing roll, a frictionally driven top back drawing roll spring-pressed thereon, a lifting plate, and a lifting plate spring, with a vibrator, a stretcher plate having a slot and a shoulder, a flexible member which passes through the slot in the stretcher plate and is fixed at one end and is attached at the other end to the lifting plate, and a medially pivoted rocking member having one end in engagement with the roving and the other end between the vibrator and the flexible member, together with setting means operative from the front of the machine to engage the flexible member with the shoulder of the stretcher plate.

5. In a spinning machine, the combination of a bottom back drawing roll, a frictionally driven top back drawing roll

spring-pressed thereon, a lifting plate, and a lifting plate spring, with a vibrator, a stretcher plate having a slot and a shoulder, a flexible member which passes through the slot in the stretcher plate and is attached at one end to the lifting plate and at the other end to an adjusting member, said adjusting member, and a medially pivoted rocking member having one end in engagement with the roving and the other end between the vibrator and the flexible member.

6. In a spinning machine, the combination of a bottom back drawing roll, a frictionally driven top back drawing roll, a spring pressed thereon, a lifting plate, and a lifting plate spring, with a vibrator, a

stretcher plate having a slot and a shoulder, a flanged spool slidable in the stretcher plate slot, a flexible member which passes through said spool and is fixed at one end and is attached at the other end to the lifting plate, and a medially pivoted rocking member having one end in engagement with the roving and the other end between the vibrator and the flexible member.

25 In testimony whereof I hereto affix my signature in presence of two witnesses.

GEORGE M. ARRAGG.
